FIG. 3.

UNITED STATES PATENT OFFICE

WILLIAM A. DE HART, OF TEANECK, NEW JERSEY, ASSIGNOR TO FRANCES ROCKEFELLER KING, OF NEW YORK, N. Y.

ELECTRIC FLATIRON

Application filed September 17, 1926. Serial No. 136,115.

My invention relates to electrically heated sad irons for laundry and domestic use, and particularly to those of the general character shown and described in Patent No. 5 1,249,638, granted December 11, 1917, to Adele Rockefeller King, and in Patent No. 1,449,201, granted March 20, 1923, to Albert H. Smith.

One object of my invention is to provide a 10 device of the aforesaid character that shall be simple and durable in construction and shall be arranged to exert relatively high pressure between the switch contacts when closed and allow a wide separation between 15 them when open. Moreover, by the arrangement of my invention the switch when closed, is independent of any slight motion or vibration of the handle of the iron and when opened or closed it acts quickly to 20 break or make the circuit.

Other objects and advantages of my invention are set forth hereinafter and a preferred embodiment thereof is illustrated in the accompanying drawings to which reference 25 may now be had as follows:

Figure 1 is a vertical longitudinal sectional elevation of an electrically heated iron embodying the present invention and illustrating the controlling switch in circuit 30 interrupting position;

Figure 2 is a detail end view of the circuit controlling switch;

Figure 3 is a view similar to Figure 1 showing the controlling switch in closed position;

Figure 4 is a plan view with the shell and attached parts removed.

The improved iron comprises a smoothing iron base 1 on which is mounted a protected 40 electric heating element 2 over which rests an insulated plate 3 supporting at the rear a block of insulating material 5 which carries the electrical terminals 6 and the parts of the 45 circuits interrupting switch hereinafter referred to. The iron is enclosed by a hollow shell 10 fitting upon and secured to the base 1 by any suitable means, the shell 10 carrying a protecting housing 11 surrounding the terminals 6 and having the movable operating

handle and switch operating parts mounted upon it as will presently be explained.

When the iron is not in use it is adapted to rest upon a suitable stand which is preferably of a double decker type illustrated in the 55 drawing in which the base plate 20 is provided with pronged feet 21 spread apart to rest upon and engage an ironing board so as to prevent sliding of the stand. The upper iron supporting plate 23 is spaced from the 60 base plate 20 by spacing collars 24 held in place by suitable bolts which pass through plates 23, 20 and the collars 24. This iron supporting stand is also preferably provided with a bail 25 pivoted in lugs 26 and arranged 65 to be moved into and out of engagement with the finger 27 projecting from the forward end of the hinged handle structure so as to hold the handle down upon the iron with circuit interrupter in closed position for the 70 purpose of heating up the iron preparatory for use.

The handle comprises a properly shaped sheet metal frame 30 pivoted at its rear lower corner upon a pin 31 mounted in the upwardly presented heavy lugs 32 cast or otherwise rigidly mounted upon the shell 10. This pivotal mounting of the handle structure permits the desired movement hereinafter explained, but limits to a minimum any side 80 play of the handle upon the iron. The projection 27 above referred to is formed upon the frame 30 as shown. A handle grip 35 is suitably mounted between the ends of the upwardly projecting arms of the frame 30. 85

Two relatively heavy leaf springs 40 and 45 are securely fastened to frame 30 to the rear of the pivot 31 and project forwardly between the handle frame and shell 10, the spring 40 engaging the top of the shell 90 while the spring 45 engages a projection from the weighted toggle member of the switch operating device presently to be described. The action of these springs 40 and 45 is to 95 hold the handle structure raised away from the iron at its forward end which gives it a slight back tilt as shown in Figure 1 of the drawings, the extent of this back tilt being limited by the connection between the handle 100

structure and the switch operating mechanism.

It will be clear that the terminals 6 co-operate with the electric contacts of the ordinary plug having the usual flexible cord conductor (not shown) which plug can be attached or detached from the iron at will and when attached serves to supply electric current from any suitable source.

One of the terminals 6 is electrically connected with one terminal of the heating element 2, while the other terminal 6 is electrically connected with one of the stationary contact members 50, 51 mounted upon the block of insulating material 5. The other stationary contact member 50 or 51 is in circuit with the other terminal of heating element 2, so that by closing the circuit through the movable element of the switch bridging contacts 50, 51, the iron will be heated. The described circuit is well known in the art and is therefore not shown in the drawings.

Cooperating with the stationary contacts 50, 51 are the movable bridging contacts 56, 57, electrically connected through a bus-bar 58 and suitably mounted in the spaced ends of an auxiliary switch frame 55 consisting of a flat bar of metal of approximate horseshoe shape. Bridging contacts 56, 57 and bus-bar 58 are suitably insulated from auxiliary frame 55.

Projecting upwardly from the insulated plate 3 and extending through slots in insulating material 5, are the spaced rigid lugs 60 in which are mounted screw journal pins 61 upon which is transversely pivoted the main switch frame 65, consisting of a metal bar bent into U-shape and of which the pivoted side arms are set at slightly less than a right angle to the connecting back portion to permit frame 65 to tilt back slightly from its pivot axis in one position. A bracket plate or block 66 is slotted at 67 to fit over the back portion of frame 65 and projects upwardly and is rigidly secured thereon centrally of said back portion by suitable means such as a pin 68 which passes through walls of the plate or block 66 and said bar 65. The plate or block 66 is also slotted in its upper edge as shown at 69 to receive a rectangular lug or flange 70 rigidly secured to and projecting downwardly from the horseshoe auxiliary frame 55. A pin 71 passes through the upper slotted end of plate or block 66 and lug or flange 70 for securing the bridging member 55 to the member 66, said pin connection allowing slight lateral rocking motion of member 55 upon member 66. The slight play allowed by the pin connection at 71 provides lateral flexibility to the bridging contact members 56 and 57 so as to automatically seat them in close contact with stationary contacts 50, 51.

The means for operating the circuit inter-
rupting switch from the pivoted iron handle

includes a pair of toggle links, one of which is in the form of a pivotally mounted weighted member while the other is connected with the pivoted handle through a third link. 75 is a weight shaped to fit in the forward contracted portion of the iron shell. This weight 75 is provided at its small end with the spaced lugs 76 which embrace a lug 77 secured to the base 1 of the iron by means of a screw 78. A pin 79 passes through lugs 76 and 77 for pivotally anchoring the member 75. The weight 75 is movable up and down upon its pivot 79 and constitutes one element of an actuating toggle, the weight of this element being not only useful as increasing the weight of the iron as a whole but also serving as a gravity toggle element to take the place of the usually employed toggle actuating springs which are very objectionable in an electrically heated iron because of the deteriorating effect of the heat upon the springs.

The member 75 is slotted in its rear upper face as indicated at 80 to receive the end of a toggle link 85 which is pivotally connected to member 75 by means of a pin 81. The link 85 is preferably formed of two spaced bars carrying in their end a cross pin or roller 86 which engages the open vertical slot 87 in the plate or block 66 above referred to, the two bars of link 85 being presented on opposite faces of the member 66. The face of the slot 87 furthest away from the pivot pin 81 extends above and below the pivotal axis 61 of the U-shaped frame 65 with the result that pressure of pin 86 of link 85 above the pivot rocks said frame and the bridging contacts carried thereby into open position as shown in Figure 1, while the pressure of said pin 86 below said pivotal axis 61 rocks said frame and bridging contact into its opposite circuit closing position as shown in Figure 3.

The handle frame 30 is formed with a slot 90 in which is mounted a block 91 having spaced perforated ears 92 to which is pivotally connected the upper end of a link 93 which passes down through a slot 94 in shell 10 and is pivotally connected at its lower end to the toggle link 85 by means of a pin 88. The link 93 is pivoted between the two bars of the link 85 and is centered therein by spacing washers 95. A stop pin 96 passes transversely through the link 93 midway of its ends to limit the upward movement of the link and the handle structure which is connected thereto.

The weight or toggle element 75 carries upon its upper face a projection 97 formed on a bridging plate 98 which extends across the recess 80 and is secured in place by screws 99. This projection 97 extends through a slot 100 in iron shell 10 and is engaged by the end of the leaf spring 45 above referred to, the pressure of the spring being added to that of the weight, the action of the weighted toggle upon the circuit closing switch is accelerated.

The weight of the toggle element 75 augmented by the pressure of spring 45 is continuously exerted upon its companion toggle link 85 which in turn continually presses against the bearing surface or wall of the slot 87 in the plate or block 66 carried by the rocking frame 65. This pressure upon the rocking frame causes the bridging contacts to be moved and held in raised circuit breaking position or lowered circuit closing position dependent upon whether the pressure of link 85 is exerted above or below the axial pivot 61. When the handle structure 30 is in raised position as shown in Figure 1, the toggle link 85 is held in raised position so that the bridging switch member 55 is also held in raised circuit breaking position. When the handle 35 is pressed downwardly into the position shown in Figure 3, the rear end of toggle link 85 is forced into the lower end of slot 87 with the result that the bridging contacts 56, 57 are thrown into circuit closing position as shown in Figure 3.

As stated above the handle frame 30 may be held in this circuit closing position by moving the bail 25 over into engagement with the finger 27 as shown in Figure 3. This latched position is suitable only when starting to ensure the proper heating of the iron. In normal operation the handle is held in the circuit closing position by the operator pressing downwardly upon the hand-grip 35, this being the natural application of pressure in the ironing operation. When the iron is in use the handle frame 30 may vibrate slightly due to variations in pressure upon it without in any way tending to open the circuit interrupter or release the pressure between the contact members. The gravity of toggle member 75 and the pressure of spring 45 hold the contacts together closely until the upward pull upon link 93 is sufficient to move the pin 86 of link 85 across the plane extending through pivotal centers 81 and 61, when the pressure of the weighted toggle elements and the spring will snap the switch into open position beyond the control of the operator. This last described action takes place when the pressure of the hand of the user is entirely released from the handle, the upward pressure of springs 40 and 45 raising the handle into the position shown in Figure 1.

The action of toggle link 85 upon rocking frame 65 is such that the bridging contacts are held in circuit closing position with a positive pressure, even under any slight movements of the handle and connected toggle during the ironing operation, this circuit closing pressure being maintained positively so long as the pin 86 engages the surface of slot 87 beneath the plane extending through centers 81 and 61. This action of the described structure is of great importance.

When the switch contacts 50, 51 are in

circuit through members 56, 57, electric heating circuit is established from one of the terminals 6 to the other through the electric heating element 2.

The arrangement of the actuating mechanism is such as to provide a quick break operation of the interrupter as already explained, and this feature is of importance to my invention since it tends to prevent an arc being established in breaking the circuit.

Attention is directed to the fact that unless the iron is on the stand it cannot be energized except when the handle is being pressed downwardly by the hand of the user. The iron is thus rendered unusually safe and the possibility of fires is minimized if not entirely obviated.

It is of course a well known fact that great numbers of fires have resulted from electric irons being left in circuit, standing on a table or board and while various switches for interrupting the circuit have been provided, it has been my aim to make a commercially operative arrangement capable of continued and satisfactory operation.

The arrangement for holding the switch closed when the iron is on the stand, forms no part of my invention, it being claimed in the Albert H. Smith Patent No. 1,449,201, granted to F. R. King on March 29, 1923.

A structure of preferred form and construction has been illustrated and described for the purpose of showing a way in which this invention may be used, but the inventive thought upon which this application is based, is broader than this illustrative embodiment thereof, and I therefore intend no limitations other than those imposed by the appended claims.

I claim:

1. The combination with a body, supporting a circuit controlling switch, of a toggle operatively connected with said controlling switch, and a spring mounted exteriorly of said body acting upon said toggle.

2. The combination with a body, supporting a circuit controlling switch, of a toggle operatively connected with said controlling switch, a handle movably mounted upon said body connected with said toggle, and a spring mounted exteriorly of said body acting upon said toggle.

3. The combination with a body, supporting a circuit controlling switch, of a toggle operatively connected with said controlling switch, a handle movably mounted upon said body connected with said toggle, a spring engaging said handle and holding the handle normally raised away from said body, and a spring mounted exteriorly of said body acting upon said toggle.

4. The combination with a body, supporting a circuit controlling switch, of a weight-

actuated toggle operatively engaging said controlling switch.

5. The combination with a body, supporting a circuit controlling switch, of a weight-actuated toggle operatively engaging said controlling switch, and a handle movably mounted upon said body connected with said toggle.

10. The combination with a body, supporting a circuit controlling switch, of a weight-actuated toggle operatively engaging said controlling switch, and a spring mounted upon said body engaging said toggle and augmenting the weight-action thereof.

15. 7. The combination with a body, supporting a circuit controlling switch, of a weight-actuated toggle operatively connected with said controlling switch, a handle movably mounted upon said body, an operative connection between said handle and said toggle, and a spring mounted upon said body and engaging said toggle to augment its action.

8. The combination with a body, supporting a circuit controlling switch, of a pair of toggle links operatively connected with said controlling switch, one of said toggle links being in the form of a pivotally mounted weight.

9. The combination with a body, supporting a circuit controlling switch, of a pair of toggle links operatively connected with said controlling switch, one of said toggle links being in the form of a pivotally mounted weight, and a spring mounted upon said body engaging said toggle link weight.

10. The combination with a hollow body, and a circuit controlling switch mounted thereon, of a toggle mounted in said hollow body and operatively connected with said controlling switch, one element of said toggle being in the form of a weight having the general contour of part of the cavity of said hollow body and pivotally anchored to said body.

45. 11. The combination with a body, and a circuit controlling switch mounted thereon, of a toggle mounted on said body and operatively connected with said controlling switch, one element of said toggle being in the form of a weight pivotally anchored to said body, a handle movably mounted upon said body and connected with said toggle, and a spring interposed between said handle and said weight element.

55. 12. The combination with a body, and a circuit controlling switch mounted thereon, of a toggle mounted on said body and operatively connected with said controlling switch, one element of said toggle being in the form of a weight pivotally anchored to said body, a handle pivotally mounted upon said body, a spring interposed between said handle and said body, and a second spring carried by said handle projecting into engagement with said weight element.

13. The combination with a body, and a circuit controlling switch mounted thereon, of a toggle mounted on said body and operatively connected with said controlling switch, one element of said toggle being in the form of a weight pivotally anchored to said body, a handle movably mounted upon said body, a spring interposed between said handle and said body, and a link connecting said handle with said toggle.

14. The combination with a body, and a circuit controlling switch mounted thereon, said switch comprising stationary and movable contacts, and said movable contact being mounted upon a pivoted frame, of a pair of pivotally connected toggle links, one of said links being pivotally anchored to said body, and the other of said links having shiftable engagement with said pivoted contact frame and adapted to exert pressure thereon either above or below a plane extending through the toggle pivot and the frame pivot.

15. The combination with a body, and a circuit controlling switch mounted thereon, said switch comprising stationary and movable contacts, and said movable contact being mounted upon a pivoted frame, of a pair of pivotally connected toggle links, one of said links being pivotally anchored to said body, and the other of said links having shiftable pin and slot engagement with said pivoted contact frame.

16. The combination with a body, and a circuit controlling switch supported thereon, said switch comprising stationary contacts and cooperating movable contacts, of a pivotally mounted frame carrying said movable contacts, a bearing face upon said frame extending above and below the pivotal axis of said frame, and a pair of pivotally connected toggle links, one of said links being pivotally anchored to said body, and the other of said links engaging the bearing face of said frame.

17. The combination with a body, and a circuit controlling switch supported thereon, said switch comprising stationary contacts and cooperating movable contacts, of a pivotally mounted frame carrying said movable contacts, a bearing face upon said frame extending above and below the pivotal axis of said frame, a pair of pivotally connected toggle links, one of said links being pivotally anchored to said body, and the other of said links engaging the bearing face of said frame, and a handle member movably mounted upon said body and connected with said other toggle link for shifting its point of engagement upon said bearing face.

18. The combination with a body, and a circuit controlling switch supported thereon, said switch comprising stationary contacts and cooperative movable contacts, of a pivotally mounted frame carrying said movable contacts, transverse pivot bearings for said

frame, an approximately vertical bearing face upon said frame extending above and below the pivotal axis of said frame, and a pair of vertically movable pivotally connected toggle links, one of said links being pivotally anchored to said body upon a transverse pivot, and the other of said links engaging the bearing face of said frame.

19. The combination of a body, and a circuit controlling switch supported thereon, said switch comprising stationary contacts, a transversely pivoted switch frame, an auxiliary frame part pivoted longitudinally upon said switch frame and capable of rocking transversely thereon, and electrically connected movable bridging contacts mounted upon said rocking auxiliary frame, a pair of pivotally connected toggle links arranged to actuate said switch frame, and a handle movably mounted upon said body and operatively connected to one of said toggle links.

20. The combination with a body and a circuit controlling switch mounted thereon, said switch comprising stationary and movable contacts, of a rocking pivoted frame upon which said movable contact is mounted, a constant pressure switch actuating link having shiftable single point engagement with said rocking contact frame and adapted to exert switch-opening and switch-closing pressure thereon, and means for shifting the point of engagement of said link with said rocking contact frame.

21. The combination with a body and a circuit controlling switch mounted thereon, said switch comprising stationary and movable contacts, of a rocking pivoted frame upon which said movable contact is mounted, a weight operated link having shiftable engagement with said rocking contact frame and adapted to exert switch-opening or switch-closing pressure thereon, and means for shifting the point of engagement of said link with said rocking contact frame.

22. The combination with a body and a circuit controlling switch mounted thereon, said switch comprising stationary and movable contacts, of a rocking pivoted frame upon which said movable contact is mounted, a constant pressure switch actuating link having shiftable single point engagement with said rocking contact frame and adapted to exert switch-opening or switch-closing pressure thereon, and a handle movably mounted upon said body and connected with said link and adapted to shift the point of engagement of said link with said rocking contact frame.

23. The combination with a body and a circuit controlling switch mounted thereon, said switch comprising stationary and movable contacts, of a pivotally mounted rocking frame carrying said movable contact, a bearing face upon said rocking frame extending above and below the pivotal axis of said frame, a switch actuating link having shift-

able engagement with the bearing face of said rocking frame, and means for shifting the point of engagement of said link with said bearing face.

24. The combination with a body and a circuit controlling switch mounted thereon, said switch comprising stationary and movable contacts, of a pivotally mounted rocking frame carrying said movable contacts, a bearing face upon said rocking frame extending above and below the pivotal axis of said frame, a switch actuating link having shiftable engagement with said bearing face and adapted to exert switch-opening or switch-closing pressure upon said rocking frame, and an operating handle member movably mounted upon said body and connected with said switch actuating link for shifting its point of engagement upon said bearing face.

25. The combination with a body, and a circuit controlling switch mounted thereon, said switch comprising stationary and movable contacts, of a pair of pivotally connected toggle links, one of said toggle links being pivotally anchored to said body, and the other of said toggle links having shiftable engagement with said movable contact, said toggle links being supported in angular or out-of-line relation to exert pressure on said movable contact in both circuit open and circuit closed positions.

26. The combination with a body, and a circuit controlling switch mounted thereon, said switch comprising stationary and movable contacts, of a pair of pivotally connected toggle links, one of said toggle links being pivotally anchored to said body, and the other of said toggle links having shiftable engagement with said movable contact, and hand operated means mounted upon said body connected with one of said toggle links to shift its engagement with said movable contact, said toggle links being supported in angular or out-of-line relation and subjected to constant actuating pressure to exert pressure on said movable contact in both circuit open and circuit closed positions.
